CLAIM

The ornamental design for a baby sleepsuit as shown and described.

DESCRIPTION

FIG. 1 is a front view of a baby sleepsuit according to the design;

FIG. 2 is a rear view of the baby sleepsuit of FIG. 1;

FIG. 3 is an enlarged detail view taken from line 3 in FIG. 1;

FIG. 4 is an enlarged detail view taken from line 4 in FIG. 2; and,

FIG. 5 is a front view of the baby sleepsuit of FIG. 1 shown with the zipper in an open configuration and the cuffs in an unfolded position.

The short-dashed long-dashed broken lines define the bounds of the enlarged detail views and form no part of the claimed design. The dash-dot broken lines define portions of the baby sleepsuit that form no part of the claimed design. The short-dashed broken lines define portions of the baby sleepsuit that form no part of the claimed design.

1 Claim, 5 Drawing Sheets
